CANDLE CUP

Robert F. Ball, Willow Grove, Pa., assignor to Country
Store Products, Inc., Warrington, Pa.

Filed May 7, 1973, Ser. No. 357,693

Term of patent 14 years

Int. Cl. D26—01; D7—01

U.S. Cl. D48—2

FIG. 1

FIG. 5

FIG. 2

FIG. 3

FIG. 4

FIG. 1 is a top and side perspective view of my new design for candle cup;

FIG. 2 is a top plan view thereof;

FIG. 3 is a bottom plan view thereof;

FIG. 4 is a continuous side elevational view as would be seen when viewed continuously peripherally around the side wall of the candle cup; and

FIG. 5 is a vertical sectional view as would be seen when viewed along line 5—5 on FIG. 2.

I claim:

The ornamental design for a candle cup, as shown.
